UNITED STATES PATENT OFFICE.

HARRY A. STANFORD AND GEORGE TUGWELL, OF CHICAGO, ILLINOIS.

FORCE-FEED OILER.

1,054,877.

Specification of Letters Patent.

Patented Mar. 4, 1913.

Application filed April 25, 1910. Serial No. 558,084.

To all whom it may concern:

Be it known that we, HARRY A. STANFORD and GEORGE TUGWELL, citizens of the United States, residing at Chicago, in the county of Cook and State of Illinois, have invented a new and useful Force-Feed Oiler, of which the following is a specification.

Our invention relates to force feed oilers in which a reciprocating piston is employed and the objects of our improvements are first, to eliminate all valves; second, to employ but two pistons for each pump which only reciprocate; third, to provide an adjustment to force a larger or smaller amount of oil; fourth, to make a simple, cheap and durable device, and other features to become apparent from the description to follow.

As is well known in the art force feed oilers are required to pump very small quantities of oil and when the mechanism employed comprises one or more valves there is always some danger of the valves not operating properly even after an adjustment of the parts has been made, therefore a device without valves like this, our present invention, is very desirable.

Our invention comprises a reciprocating piston, fitted to move in a cylinder and provided with a cavity in its end into which is fitted another reciprocating piston, the first named piston being provided with a suitable port and operated by suitable mechanism.

To describe our invention so that others versed in the art to which it pertains can make and use the same, we have illustrated it on the accompanying two sheets of drawings forming a part of this specification in which:

Figure 1, is a front elevation of a device comprising our invention; Fig. 2, is a similar view partly in section; Fig. 3, is a section on line 3—3 of Fig. 2; Fig. 4, is a section on line 4—4 of Fig. 2.

Similar reference characters refer to similar parts throughout the several views.

The operating mechanism is contained in a suitable oil receptacle 6, having the bottom 7, vertical walls 8 and top 9. Within the receptacle 6 are located any desired number of cylinders 10 which are rigidly secured to one wall of receptacle 6 by screws 11 or otherwise, and the cylinders 10 may or may not be made integral. Since the cylinders 10 are identical in construction and operation we will proceed to describe a single cylinder and its coöperative parts. Pro-

vided to snugly fit the bore of cylinder 10 is the piston 12 provided with the large bore 13 and small bore 14 in its upper end forming the offset 15 at the junction of said two bores. A second piston 16 is provided to fit snugly into the bore 13 and has a reduced lower end 17 to fit snugly into the bore 14. The offset 18 formed at the junction of piston 16 and reduced portion 17 is the same distance from the extreme end 19 as is the offset 15 from the bottom or lower end 20 of bore 14, so that when the offset 18 rests on offset 15 the end 19 will rest on the bottom 20 of bore 14.

A port 21 leads from the lower end of bore 14 to the exterior of piston 12 and the two ports 22 and 23 lead from the lower end of bore 13 to the exterior of the piston 12. When the piston 12 is in its lowermost position as seen in Fig. 4, the port 21 communicates with the interior of receptacle 6, the port 22 is closed by the wall of cylinder 10 and the port 23 communicates with the passage 24 which leads to the drip funnel 25 above the top 9. When the piston 12 is in its uppermost position the port 23 is closed by the wall of cylinder 10, the port 22 is about in line with the discharge passage 26 and the port 21 is at the upper edge of the sight discharge passage 27 which leads to the sight drip spout 28; while the shoulders 29 on piston 16 rest against the underside of the top 9 and the offsets 18 and 15 are contacting. The shoulders 29 on piston 16 are formed by flattening the two opposite sides of the upper end of said piston 16 which extends loosely through a hole in the top 9 and is screw-threaded. A screw nut 30 is placed on the upper end of piston 16 above top 9 and is held against turning by the locking plate 31. The piston 16 is held against turning by means of the elongated hole in top 9 through which the flattened portion of the piston passes.

In operation the piston 12 is moved up and down from its lowermost position to its uppermost position and back to its lowermost position, continually. The receptacle 6 is filled with oil to any level above the lower end of cylinder 10, for example to the level indicated by the dotted line 32. As the piston 12 moves up from the position shown in Fig. 4, the piston 16, by reason of its frictional contact with piston 12 will also move up until its shoulders 29 come in contact with the top 9. The continued upward movement of piston 12 will force the oil out

from between the bottom 20 of bore 14 and the lower end 19 of reduced piston portion 17 into passage 27, from whence the oil passes out at drip spout 28 and into passage 24; and at the same time the continued upward movement of piston 12 will force the oil out from between the offset 18 and offset 15 into the passage 26. As the piston 12 moves down again the piston 16 will move downward with it until the screw nut 30 contacts with the top 9; the continued downward movement of piston 12 will, by means of the vacuum created, draw oil into the space between the bottom 20 of bore 14 and the lower extremity 19 of reduced piston portion 17. Thus it will be seen that the oil is drawn from within receptacle 6, is forced through passage 27, drips at 28 into passage 24 from whence it is drawn and forced out through passage 26 from whence it is directed by means of piping 33 to any desired locality.

A transparent protecting cap 34 is secured over the exposed parts of passages 27 and 24 to exclude all foreign matter and permit seeing the oil drip from spout 28 into drip funnel 25.

While any desired means may be employed to reciprocate the piston 12 without departing from the spirit of my invention, I have shown a novel and suitable mechanism to cause said movement which comprises a horizontal shaft 35 mounted in suitable bearings rigid with cylinder 10, and having mounted rigidly thereon two eccentric cams 36 which operatively engage the slotted levers 37 pivotally mounted at 38 to brackets rigid with cylinder 10. The free end of levers 37 are connected by links 39 to a bar or shaft 40 which extends through a hole provided therefor in the lower end of pistons 12. The parts are so arranged and connected that as the shaft 35 is rotated the pistons 12 will be reciprocated longitudinally.

Loosely mounted on shaft 35 is a worm gear 41 which meshes with the worm 42 mounted on shaft 43 mounted in suitable bearings rigid with the receptacle 6, said shaft having one end extending to the exterior of said receptacle 6 where power is applied to the same from any source desired. Rigidly secured to the shaft 35 adjacent to gear 41 is a collar 44 which is provided with notches into which a spring pressed latch 45 slidably mounted in the hub of gear 41 takes, in such manner that when the gear 41 rotates in one direction it will by reason of latch 45 carry the collar 44 and therefore the shaft 35 around with it, but if the gear 41 rotates in the other direction the latch 45 simply clicks over the notches in collar 44 and said collar and shaft 35 are not rotated.

The purpose of some such connection between the gear 41 and shaft 35 is to permit the rotating of shaft 35 in one direction 65 while the gear 41 remains stationary or to rotate the shaft 35 at a greater speed than that at which the gear 41 is rotating.

A short shaft 46 extends through a bearing and stuffing box 47 in one wall 8 of the receptacle 6 to the exterior and forms a continuation of shaft 35. The shaft 46 is coupled to shaft 35 in any convenient manner as by a cross pin 48 taking into the slot 49 in the end of collar 44; and the protruding end of shaft 46 is squared to permit the attaching of a handle to rotate the same.

While we have shown and described a construction and form which at present is considered the best, we may find from further experience that a change in the general arrangement and form of parts may improve the device, which change may be made without departing from the scope of the invention as pointed out in the appended claims.

Having thus fully described our invention what we claim as new and desire to secure by Letters Patent of the United States is:—

1. In a device of the class described, a cylinder open at both ends, a hollow piston 90 having one end closed to reciprocate in said cylinder, a second piston to move in said hollow piston, a port in said first named piston forming communication between the interior and exterior of said piston to cooperate with two ports through the cylinder, 95 abutments on the second named piston to engage a stationary part to limit the movement of said piston and means whereby lost motion is provided between said second 100 named piston and the stationary part.

2. In a device of the class described, a stationary cylinder open at both ends, a piston fitted to move in said cylinder, a large and small longitudinal bore in one end 105 of said piston, a second piston having a large and a small portion to fit and move in the bores of said first named piston, a port in said first named piston leading from the exterior to the small bore, a second por. in 110 said first named piston leading from the exterior to the large bore, three internal passages in said cylinder to coöperate with said ports in said piston and means to reciprocate said first named piston.

In testimony whereof we have signed our names to this specification in presence of two subscribing witnesses this 5th day of February, 1910, at Chicago, Illinois.

HARRY A. STANFORD.
GEORGE TUGWELL.
